(57) **CLAIM**

The ornamental design for an oral irrigator, as shown and described.

DESCRIPTION

FIG. 1 is a rear-top perspective view of an oral irrigator. FIG. 2 is a rear-bottom perspective of the oral irrigator of FIG. 1

FIG. 3 is a rear view of the oral irrigator of FIG. 1.

FIG. 4 is a front view of the oral irrigator of FIG. 1.

FIG. 5 is a left-side view of the oral irrigator of FIG. 1.

FIG. 6 is a right-side view of the oral irrigator of FIG. 1.

FIG. 7 is a top view of the oral irrigator of FIG. 1; and,

FIG. 8 is a bottom view of the oral irrigator of FIG. 1.

The broken lines shown in the drawings illustrate portions of the article and form no part of the claimed design.

1 Claim, 7 Drawing Sheets
